US0D1079348S

(12) United States Design Patent (10) Patent No.: US D1,079,348 S
(45) Date of Patent:  Jun. 17, 2025

(54) TABLE

(71) Applicant: EDRA SPA, Perignano (IT)
(72) Inventor: Iacopo Emilio Foggini, Perignano (IT)
() Term: 15 Years
(21) Appl. No.: 35/518,813
(22) Filed: Oct. 6, 2023

(80) Hague Agreement Data

Int. Filing Date: Oct. 6, 2023
Int. Reg. No.: DM/232449
Int. Reg. Date: Oct. 6, 2023
Int. Reg. Pub. Date: Oct. 27, 2023

(30) Foreign Application Priority Data

Apr. 18, 2023 (EM) 015018486-0003
Apr. 18, 2023 (EM) 015018486-0004
Apr. 18, 2023 (EM) 015018486-0005

(51) LOC (15) Cl. 06-03

(52) U.S. Cl.

USPC D6/691.8
